J. HORRIDGE

MACHINE FOR COMBING COTTON, WOOL, AND THE LIKE

Filed May 5, 1923.

FIG. 2

FIG. 3

FIG. 4

FIG. 1

INVENTOR:

BY *James Horridge*
Mr Wallace White
ATTY.

UNITED STATES PATENT OFFICE.

JAMES HORRIDGE, OF BOLTON, ENGLAND, ASSIGNOR TO JOHN HETHERINGTON AND SONS LIMITED, OF MANCHESTER, ENGLAND.

MACHINE FOR COMBING COTTON, WOOL, AND THE LIKE.

Application filed May 5, 1923. Serial No. 636,816.

To all whom it may concern:

Be it known that I, JAMES HORRIDGE, a subject of the King of Great Britain, residing at Bolton, in the county of Lancaster, 5 England, have invented new and useful Improvements in or Relating to Machines for Combing Cotton, Wool, and the like, of which the following is a specification.

The invention relates to improvements in 10 machines for combing cotton, wool and the like, and has for its object to construct a comb cylinder for such machines in such manner that the comb segment thereof can be readily removed without disturbing the 15 other part of the cylinder.

In the accompanying drawings—

Figure 1 is an end view of the improved cylinder.

Figure 2 is a side elevation, partly in 20 section, of the comb or needle carrying part thereof.

Figure 3 is a side elevation, partly in section, of the cylinder assembled and

Figure 4 is a transverse section taken on 25 the line A B of Figure 3.

Referring to the drawings—1 represents the body of the cylinder, which is fixed upon the shaft 2, driven from the main driving shaft of the machine by the usual gearing.

30 The body 1 of the cylinder comprises a portion having a comparatively large diameter and a portion 1^a having a comparatively small diameter embracing the shaft 2 and said body 1 is fixed upon the shaft 2 by means of set screws 3 and is furnished with end flanges 4, and embracing the part 1^a of the body 1 in a saddle-like manner, as shown, 35 is a comb circle or segment 5 upon which the needles 6 are mounted, the two parts

being secured together by means of set 40 screws 7 which are passed through holes or perforations 8 in the end flanges 4 and screw into holes or recesses 9 in the comb segment or circle 5 as shown.

By these means the comb-circle or segment 5 can be readily removed by unscrewing the set screw 7 leaving the body 1 of the cylinder upon the shaft 2 and thus preventing the necessity for removing the whole cylinder from its shaft which usually entails dismantling part of the gear with the consequent expenditure of time and labor.

What I claim as my invention and desire to secure by Letters Patent is:—

1. In a combing machine having a cylinder shaft, a cylinder comprising a pair of semi-cylindrical portions secured together to form a body having greater radius along one-half thereof than the other, means for securing said cylinder to said shaft, a needle 55 segment adapted to embrace the half of the cylinder having the smaller radius, and means for securing the segment to said cylinder half.

2. In a combing machine having a cylinder shaft, a cylinder comprising a pair of semi-cylindrical portions secured together to form a body having greater radius along one-half thereof than the other, means for securing said cylinder to said shaft, a needle 60 segment adapted to removably embrace the half of the cylinder having the smaller radius, and means for securing the segment to said cylinder half.

In testimony whereof I have signed my 75 name to this specification.

JAMES HORRIDGE.
